UNITED STATES PATENT OFFICE

PASQUALE GALASSI, OF NEW YORK, N. Y.

TERRAZZO-FLOORING DIVIDING STRIP

Application filed January 18, 1928. Serial No. 247,620.

This invention relates to terrazzo and similar floors and more particularly refers to improvements in dividing strips such as are used in terrazzo floors for dividing the floor surface into a number of panels or units, producing a variety of decorative designs, at the same time preventing or localizing cracks in the floor.

Terrazzo, granolithic and similar floors usually comprise a lower bed or layer of concrete, cement, mortar or other suitable material which is spread in semi-liquid form of the proper consistency on the floor foundation, and an upper or finishing layer of better grade material generally consisting of a mixture of marble chips and cement, by means of which a good durable surface can be obtained as well as design and color effects of great variety.

In order to prevent or localize cracks in the upper layer of the floor, the same is generally divided into a number of units or panels by means of dividing strips arranged to form a predetermined design. Said dividing strips generally consist of metal strips set on edge on or through the lower layer with their upper edge level with the surface of the floor. The same are generally provided with suitable anchoring means and are also useful as a gauge or means for delimiting the total depth of the finishing layer of the floor.

The strips are generally made of a relatively soft metal, such as brass, the wearing qualities of which are approximately equal to those of the material out of which the floor proper is composed. Floors obtained in this manner are relatively inexpensive and durable, they have a rich appearance and take a high polish; for this reason they are also desirable from a sanitary standpoint because they can easily be kept clean.

However, in a great many instances, the extremely smooth surface of these floors is objectionable from the standpoint of safety, because on account of it the floors are apt to be rather slippery and may be the direct cause of accidents, especially in public places, corridors and halls, and more particularly where the floor slopes down to an incline, in stairways, etc.

In such places therefore, it has heretofore been customary to add to the floor composition, some ingredient or ingredients imparting to it effective anti-slip properties; for instance, by adding a certain amount of alum-dum, or carborundum or emery or quartz sand, etc., to the ordinary mixture of marble chips and cement, the resulting floor will have a surface possessing highly frictional and adhesive properties.

On the other hand, floors thus produced are not entirely satisfactory because their cost is much higher than that of ordinary terrazzo floors and also because they quickly and easily collect dirt and dust which can only be removed in part and with considerable difficulty.

Furthermore, the appearance of such floors is not as good as that of ordinary terrazzo floors, their texture being darker and their surface being rather dull.

In another patent application entitled, Flooring strip, filed simultaneously herewith, I have described and claimed a special type of dividing strip comprising a metallic supporting member, and a heading carried thereby, said heading being formed out of anti-slip material such as lead or some suitable anti-slip composition.

Such a type of strip may be used in place of other strips of the ordinary type, and will produce novel decorative effects, and will at the same time impart anti-slip properties to the floor without materially increasing its cost or marring its appearance.

The primary object of this invention is to provide a dividing strip of a novel and improved construction which is relatively inexpensive to manufacture and which is well adapted for use in floors or pavements of large dimensions; said strip being adapted to impart desirable anti-slip properties to the floors or pavements where they are employed, without materially affecting their cost of production and appearance.

Another object of this invention is to provide a new and improved type of dividing strip, said strip being formed out of a suitable anti-slip composition cast or molded or extruded in suitable sections and lengths.

A further object is to provide a floor dividing strip of a novel and improved design, comprising a body made of anti-slip composition, 5 molded or cast or extruded in suitable sections and lengths, and an internal metallic core acting as a reinforcement and binder for the entire structure.

Other objects and advantages of the present invention will more fully appear as the description proceeds and will be set forth and 10 claimed in the appended claims.

Various embodiments of my invention are illustrated in the drawings, in which:

Fig. 1 is a plan view of a typical terrazzo 15 floor, showing how the strips are applied in position;

Fig. 2 is a fragmentary sectional view in perspective of a dividing strip embodying my invention;

20 Figs. 3, 4 and 5, are similar views of other strips of different designs also embodying my invention;

Fig. 6 is a sectional elevation of a terrazzo 25 floor, with still another type of strip embodying my invention in position; and

Fig. 7 is a sectional elevation of a similar floor illustrating still another dividing strip of a different construction.

My improved strip comprises essentially a 30 length of anti-slip material such as lead, or a suitable composition such as cementitious material including an anti-slip aggregate, and a metallic core therefor, acting as a binder and reinforcement for the completed structure. The core is entirely embedded in the 35 anti-slip material, or cement composition and therefore it can be made of inexpensive material such as iron or mild steel.

In Fig. 1, 10 designates a terrazzo floor, 40 comprising a number of adjoining panels or units 11, separated by dividing strips 12.

In Fig. 2, I illustrate a strip comprising a relatively narrow body 13 of cementitious material including anti-slip aggregate, 45 formed with a laterally extending flange 14 and having its lower end tapering down to an edge 15. Said body portion is obtained by forming or pressing the material about a suitable core 16, which is formed of corrugated 50 sheet metal, having substantially a T section tilted to one side.

The structure thus obtained can be placed in position merely by forcing its lower portion through the bed or lower layer of the floor 55 until the lower surface of flange 14 comes to rest on the upper surface of said bed or foundation layer. The distance between the lower surface of flange 14 and the upper surface of body 13 is preferably made to correspond to 60 the thickness of the finishing layer of the floor; so that when the strip is laid in position, its portion projecting above the surface of the foundation layer acts as a guide and gauge for the pouring of the finishing layer.

65 A strip of this character as stated, is pref-

erably made of anti-slip material, but can also be made of ordinary cement if desired, when no anti-slip properties in the floor are required.

This type of strip is particularly suitable 70 for large floors, pavements, sidewalks, etc., where ordinary brass dividing strips having the necessary rigidity and thickness would entail prohibitive costs.

My inventive idea may be applied in a 75 number of ways, as the drawings show; for instance, in Fig. 3, I illustrate a strip, the body of which has a section composed of an upper trapezoidal portion 17, and a lower triangular section 13, joined along the lines 19, 20. The pointed lower end thus obtained, facilitates the placing of the strip in position through the foundation layer and the meeting edges 19, 20 serve to define the depth at which the strip should be laid.

At the same time the slanted sides of the trapezoidal portion 17 cause the strip to remain wedged in the material of the floor after setting, thus insuring the stability of the strip. The strip is also provided with a core 80 having a cross section 21.

A somewhat similar strip is illustrated in Fig. 4 where the upper trapezoidal portion 22 and the lower triangular portion 23 are joined by an intermediate rectangular portion 24. In this case, the core is shown as being formed of a simple strip of sheet metal 25, preferably corrugated in order to increase its rigidity.

Still another type of strip is illustrated 100 in Fig. 5 where a trapezoidal head portion 26 is provided with a depending narrower rib portion 27 having a pointed lower end 28, the strip being also in this case provided with a core 29.

In Fig. 6, 30 designates a floor foundation, 31 the floor foundation layer or bed, and 32 the finishing layer of the floor. The strip 33 illustrated, is somewhat similar to the one shown in Fig. 2, except that it has two lateral flanges 34, 35, instead of one, the body of the strip being built about a core having a cross section 36.

It will be observed that the lower portion of the strip is inserted through the foundation layer of the floor and that the strip remains supported by said foundation layer, when the lower surface of flanges 34, 35, reaches the upper surface of said foundation layer. This also insures a correct vertical alignment of the strip, and defines the depth of the finishing layer.

The upper surface 37 of the strip will therefore be on a level with the upper surface 38 of the floor. It will also be observed that the two flanges act as anchoring means for the strip, preventing the same from coming off after the floor has set.

A similar application is shown in Fig. 7 where 39 is the floor foundation, 40 is the 130

foundation layer and 41 is the finishing layer. The strip 42 shown, is made with a rail section, comprising a trapezoidal head 43, a rib portion 44 and a flange portion 45 and its total height corresponds to the depth of the finishing layer of the floor. The body of the strip is built about a core portion 46 having a downwardly extending rib member 47, outwardly projecting from the lower surface of flange 45. This provides a type of strip which can be laid in position without any difficulty, its rib member 47 being very thin and easily inserted through the foundation layer even when its material has reached a high degree of consistency; furthermore, it provides a lighter construction than those previously described.

As stated in the course of this description, although strips made according to my invention are preferably of an anti-slip nature, it is within the scope of my invention to produce them out of any suitable material, such as cement, for instance, independently of whether it possesses anti-slip properties or not.

From the foregoing, it can be seen that my inventive idea may be applied in a number of ways, and therefore, the drawings will be understood as being intended for illustrative purposes only and not in a limiting sense. I accordingly reserve myself the right to carry my invention into practice in all those ways and manners which may enter, fairly, into the scope of the appended claims.

I claim:

1. As a new article of manufacture, a pre-formed floor strip for terrazzo floors or the like for dividing the floor composition into panels conforming to a desired design, comprising an individual unitary straight strip comprising cementitious material including anti-slip aggregate to present an anti-slip surface, adapted to meet an adjoining strip of the same construction at any angle necessary to produce the desired design in the floor.

2. As a new article of manufacture, a pre-formed floor strip for terrazzo floors or the like for dividing the floor composition into panels conforming to a desired design, comprising an individual unitary straight strip comprising cementitious material including anti-slip aggregate to present an anti-slip surface, adapted to meet an adjoining strip of the same construction at any angle necessary to produce the desired design in the floor, said strip having lateral projections for anchoring the strip.

3. A terrazzo or similar floor comprising a body of floor composition comprising marble chips and cement and a plurality of individual straight strips for dividing said body into a plurality of panels conforming to a desired design, and for imparting anti-slip properties to said floor, each strip formed of cementitious material including anti-slip

aggregate to present an anti-slip surface, and adapted to meet an adjoining strip of the same construction at an angle necessary to produce the desired design of panels in the floor.
